FLUSH DRAWER PULL

Fritz C. Benson, West Haven, Conn., assignor to The
H. B. Ives Company, New Haven, Conn., a corporation
of Connecticut

Filed Jan. 22, 1960, Ser. No. 59,141

Term of patent 14 years

(Cl. D10—8)

Fig. 1.

Fig. 2.

Fig. 3.

FIG. 1 is a front elevational view of a flush drawer pull embodying my new design;

FIG. 2 is a similar view with the handle in operative position; and

FIG. 3 is a sectional view on line 3—3 of FIG. 2.

My design for the flush drawer pull shown is characterized by the unbroken convex back panel and the specific swinging semicircular handle.

I claim:

The ornamental design for a flush drawer pull, as shown and described.
